(57) **CLAIM**

The ornamental design for a mounting bracket, as shown and described.

DESCRIPTION

FIG. 1 is a front isometric view of a mounting bracket, showing my new design;

FIG. 2 is a bottom isometric view thereof;

FIG. 3 is a rear view thereof;

FIG. 4 is a front view thereof;

FIG. 5 is a top view thereof;

FIG. 6 is a bottom side view thereof;

FIG. 7 is a right-side view thereof; and,

FIG. 8 is a left side view thereof.

The broken lines of FIGS. 1-6 illustrate environmental matter and form no part of the claimed design.
